UNITED STATES PATENT OFFICE.

LEMUEL F. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 30, 1923. Serial No. 660,146.

To all whom it may concern:

Be it known that I, LEMUEL F. HOWARD, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus of the type wherein train carried governing mechanism is controlled by energy received from the trackway. More specifically the present invention relates to the train carried portion of such apparatus.

I will describe one form of apparatus embodying my invention, and will then point out the novel features thereof in claims.

20 In the accompanying drawing, Fig. 1 is a diagrammatic view showing one form of apparatus embodying my invention. Fig. 2 is a view showing a modification of a portion of the apparatus shown in Fig. 1 and 25 also embodying my invention.

Similar reference characters refer to similar parts in each of the views.

Referring first to Fig. 1, the reference character A designates a train carried relay, 30 which, as here shown, is of the induction motor type comprising two stator windings 10 and 11, a rotor 12 and three contact fingers 2, 3 and 4 operated by the rotor. The stator windings 10 and 11 are supplied 35 with energy controlled by traffic conditions in advance of the train in such manner that under proceed traffic conditions the contact fingers are swung to the right, under caution traffic conditions the contact fingers are 40 swung to the left, and under stop traffic conditions the contact fingers occupy vertical or intermediate positions. The means for supplying current to the windings 10 and 11 forms no part of my present invention 45 and is omitted from the drawing for the purpose of simplicity.

Also located on the train is a signal S, comprising in the form here shown, three lamps G, Y and R, which lamps, when 50 lighted, indicate "Proceed," "Caution" and "Stop," respectively. The proceed lamp G is controlled by contact 2-2^a of relay A, so that this lamp is lighted under proceed traffic conditions. The caution lamp Y is

controlled by contact 2-2^b of relay A, so 55 that this lamp is lighted under caution traffic conditions. The stop lamp R is controlled by contact 2-2^c of relay A, so that this lamp is lighted under stop traffic conditions. The circuits for these lamps as well as for the other parts of the apparatus are shown in skeleton form, in that the two terminals of the battery or other source of current are represented by the letters B and O. These circuits will be clearly understood 60 from the drawing.

Contact finger 4 of relay A controls the brakes of the train in the following manner: When contact 4-4^a is closed, a slow releasing relay C is energized through a circuit which will be obvious from the drawing. When relay C is energized, a magnet 6 is also energized through front contact 13, the circuit for which magnet will also be obvious from the drawing. Magnet 6 controls 70 the brakes in such manner that an automatic application occurs when this magnet is de-energized. As here shown, magnet 6 is provided with an armature 7, which controls a valve 5 in a pipe D. As long as magnet 6 is energized valve 5 is closed and no automatic application of the brakes occurs; when magnet 6 becomes de-energized, however, it releases armature 7, thereby permitting valve 5 to open and the consequent 75 opening of pipe D to atmosphere causes an automatic application of the brakes to occur.

The reference character E designates a 80 train carried relay which is provided with a pick-up circuit including a caution contact 4-4^b of relay A and a normally open circuit controller F so located that it may be manually closed by the driver of the train. When the relay is once closed, it will remain 85 closed as long as contact 4-4^b is closed, because of the stick circuit including contact 4-4^b and a front contact 9 of relay E. When relay E is closed, contact 8 thereof closes an auxiliary circuit for brake-controlling magnet 6, so that this magnet then 90 remains energized after relay C becomes de-energized.

The reference character X designates an 95 auxiliary signaling device, which, in the form here shown, is an electric lamp controlled by caution contact 3-3^b of relay A. This lamp X is so designed that in the ab-

sence of resistance in its circuit it will burn at greater brilliancy than the lamps of signal S. The circuit for lamp X includes a ballast resistance unit 10, that is, a unit 5 having a high positive temperature coefficient, so that the resistance of the unit increases with increase of temperature. It follows that when contact 3-3^b of relay A becomes closed, the auxiliary lamp X will 10 momentarily burn at relatively high brilliancy and will subsequently burn at relatively low brilliancy.

The operation of the apparatus shown in Figure 1, is as follows: When relay A is 15 energized in proceed direction, as shown in the drawing, the proceed lamp G is lighted, slow-releasing relay C is energized, and brake controlling magnet 6 is also energized, so that the train may proceed without an 20 automatic application of the brakes. When such a change in traffic conditions occurs as to cause relay A to become energized in the caution direction, lamp G will become extinguished, lamp Y will become lighted, and relay C will become de-energized, so that 25 after a certain interval of time this relay will open and the brakes will be automatically applied unless the driver takes suitable action to prevent such application. If, 30 during the said interval of time, the driver closes circuit controller F, relay E will become energized, thereby closing the auxiliary circuit for magnet 6 and preventing an automatic application of the brakes. Relay 35 E will then remain energized through its stick circuit as long as relay A continues to be energized in the caution direction. As soon as relay A assumes the caution position, lamp X is momentarily lighted at 40 excess brilliancy, thereby emphatically calling the driver's attention to the fact that a change has occurred in the indication given by signal S. It is not necessary, therefore, 45 for the driver to constantly watch the signal S, because when this signal changes to an indication requiring action on the part of the driver, his attention will be called to this fact by the brilliant illumination of lamp X. Preferably lamp X, when 50 brilliantly lighted, will be visible to the driver no matter what part of his cab he may be occupying and no matter in what direction he may be looking.

The apparatus shown in Fig. 2 is the same 55 as that shown in Fig. 1, except that the auxiliary lamp X is omitted, the caution lamp Y has the same characteristic as lamp X, and the ballast resistance 10 is placed in the circuit of the lamp Y. When relay A 60 changes from the proceed to the caution position, lamp Y will momentarily be lighted at excess brilliancy and will then be reduced to normal brilliancy, so that the driver's attention is emphatically called to the change in indication given by signal S.

One important feature of my invention is the fact that I am assured that the driver's attention will be immediately called to a change of indication requiring action on his part, so that I am enabled to materially reduce the time interval required in which to permit the driver to prevent an automatic brake application by closing circuit controller F.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Train carried traffic controlling apparatus comprising a signal device provided with a circuit including a source of current and means for closing and opening the circuit, and a ballast resistance in said circuit for reducing the amount of current supplied to said signal device after the circuit has been closed for a brief interval of time.

2. Train carried traffic controlling apparatus comprising at least two signaling devices giving a less restrictive and a more restrictive indication respectively, circuits for said devices, and a ballast resistance associated with the circuit for the more restrictive device to reduce the current supplied to such device after its circuit has been closed for a brief interval of time.

3. Train carried traffic controlling apparatus comprising at least two signaling devices giving a less restrictive and a more restrictive indication respectively, circuits for said devices, and means associated with the circuit for the more restrictive device for permitting an excessive current to reach the device for a brief interval after the circuit is closed and for thereafter reducing the current in said device to normal value.

4. In combination, a train carried main signal capable of giving a less restrictive indication and a more restrictive indication, an auxiliary signal device energized only when the more restrictive indication is given by said main signal, and a ballast resistance in the circuit for said auxiliary signal device.

5. In combination, a train carried railway signal comprising at least two lamps giving a less restrictive and a more restrictive indication respectively, and means for causing the more restrictive indication lamp to burn momentarily at excess brilliancy when such lamp becomes lighted.

6. In combination, a train carried railway signal capable of giving a less restrictive indication and a more restrictive indication, an auxiliary lamp arranged to be lighted only when the more restrictive indication is

given by said signal, and means for causing said lamp to burn momentarily at excess brilliancy when the lamp becomes lighted.

7. Train carried railway signaling apparatus comprising a lamp provided with a circuit including a source of current and means for closing and opening the circuit, and a ballast resistance in said circuit for causing said lamp to burn momentarily at relatively high brilliancy when the circuit becomes closed and subsequently causing the lamp to burn at relatively low brilliancy.

8. Train carried railway traffic controlling apparatus comprising means operating to apply the brakes automatically after a

given interval of time subsequent to a change from a less restrictive to a more restrictive traffic condition, signaling means for indicating traffic conditions to the driver of the train, means for preventing such automatic application if the driver takes suitable action during such interval of time, and means for emphatically calling the driver's attention to a change from less to more restrictive traffic conditions thereby insuring that he have an opportunity to take such suitable action during said time interval.

In testimony whereof I affix my signature.

LEMUEL F. HOWARD.
